UNITED STATES PATENT OFFICE.

MARGARET A. WIGGIN, OF TOPEKA, KANSAS.

DESIGN FOR A CLOTHES-HANGER BASE.

No. 39,270.

Specification for Design.

Patented April 21, 1908.

Application filed November 22, 1907. Serial No. 403,405. Term of patent 7 years.

To all whom it may concern:

Be it known that I, MARGARET A. WIGGIN, a citizen of the United States of America, residing at Topeka, in the county of Shawnee and State of Kansas, have invented a new, original, and ornamental Design for Clothes-Hanger Bases, of which the following is a specification, reference being had to the accompanying drawing, forming part thereof.

The figure is a plan view of a clothes hanger base for sleeping cars and other purposes, showing my new design.

I claim—

The ornamental design for a clothes hanger base as shown.

MARGARET A. WIGGIN.
